United States Patent Office.

WILLIAM R. NICHOLS, OF PHILADELPHIA, PENNSYLVANIA.

Letters Patent No. 78,120, dated May 19, 1868.

IMPROVED CAR-SPRING.

The Schedule referred to in these Letters Patent and making part of the same.

TO ALL WHOM IT MAY CONCERN:

Be it known that I, WILLIAM R. NICHOLS, of Philadelphia, Pennsylvania, have invented an Improved Car-Spring; and I do hereby declare the following to be a full, clear, and exact description of the same.

My invention consists of an improvement, described hereafter, in the car-spring for which Letters Patent were granted to me on the third day of July, 1866, the object of my improvement being to dispense with the cumbrous and costly cast-iron box described in that patent.

In order to enable others skilled in the art to make and use my invention, I will now proceed to describe its construction and operation, reference being had to the accompanying drawing, which forms a part of this specification, and in which—

Figure 1 is a side view of my improved car-spring.

Figure 2, a sectional view.

Figure 3, a transverse section on the line 1-2, fig. 2.

Figures 4 and 5, longitudinal sections on the line 3-4, fig. 3, drawn to an enlarged scale, and showing different modes of retaining the layers of steel bars composing the spring; and

Figure 6 an inverted perspective view of one of the pockets or saddles.

Similar letters refer to similar parts throughout the several views.

Two springs, A and A', fig. 3, are, in the present instance, combined, each spring being composed of three layers of bar-steel, a, b, and c, fig. 2, the inner layer, a, being bent to the elliptical form shown, and its opposite ends being bevelled and lapped together at y, fig. 2, while the second layer, b, is bent to a corresponding form, its opposite ends being bevelled and lapped together at x, fig. 2. The outer layers, c, although forming a component part of the spring, are not continuous, but terminate at m m. Each spring may consist of any desired number of layers, according to the rigidity and elasticity desired.

In my former patent, of July 3, 1866, springs composed of layers, as described, and simply riveted together where the laps occur, are confined in a box having a loose cover. I have found, however, that by properly securing the layers together, and adapting the springs to a suitable pocket or saddle, the cumbrous box may be dispensed with.

It will be seen that the layers at the top and bottom of the spring are fitted to a sleeve, B, and secured thereto either by riveting, as shown in fig. 4, or by forming protuberances on one layer to fit into a recess in the adjacent layer, as seen in fig. 5. The layers are thus effectually secured where the lap-joints occur; but as a further security, and with a view of combining the two springs, so as to form one entire self-contained spring, I make use of two cast-iron pockets or saddles, D, in a manner which I will now proceed to describe.

In the present instance, the saddle is constructed for the two springs A and A', but it may be made for a single spring only, or for more than two springs.

The saddle consists of a plate, d, with two projecting flanges, e e, and an intermediate central rib, f. Recesses h h are formed, one for the reception of the sleeve B of one spring, and the other for that of the other spring, the layers composing each spring being confined laterally between one of the flanges e and the central rib f. The saddles are adjusted to the springs as shown in figs. 2 and 3, and are confined thereto by cross-bars i i fitting between the flanges e e of the saddle, one on each side of and in contact with the sleeve B, where they are secured by screws or rivets, j, passing into or through the central rib f of the saddle.

It should be clearly understood that in compressing the springs the saddles bear upon the sleeves B only, and are always free from contact vertically with the layers, no matter how far the spring may be compressed, the plate d of the saddle being so formed that it can never come in contact with the layers, (see fig. 2.) In fact the object of the saddle is not to add rigidity to the springs, but to assist in maintaining the component parts of each spring in their proper lateral position, and to so combine two or more springs that the whole will form one entire self-contained car-spring.

I claim as my invention, and desire to secure by Letters Patent—

One or more springs, each of which is composed of one or more layers, in the manner described, in combination with saddles constructed and adapted to the said spring or springs, substantially as specified.

In testimony whereof, I have signed my name to this specification in the presence of two subscribing witnesses.

WILLIAM R. NICHOLS.
